METHOD OF MANUFACTURING FLAT-IRONS
AND THE LIKE

Joseph W. Myers, Philadelphia, Pa., assignor, by
mesne assignments, to Proctor & Schwartz,
Inc., Philadelphia, Pa., a corporation of Penn-
sylvania

Application April 2, 1935, Serial No. 44,841

10 Claims. (CL 219—25)

This invention relates to the manufacture of electrical appliances, such as flat-irons, and particularly to processes of manufacturing the heating units of such appliances. The invention is directed specifically to that class of electrical appliances in which the electrical element is positioned within a cavity or recess of the appliance. The invention is intended primarily for application to electric flat-irons, in which the heating element is disposed within a cavity or recess in the sole plate of the iron, but the invention is not thus limited and is applicable to other appliances and, in fact, has utility in any instance where the desired purpose may be served. For the purpose of disclosure, the invention will be described with particular reference to an electric flat-iron.

It is now common practice in the manufacture of an electric flat-iron to imbed the heating element in the form of a coil in refractory insulating material within a cavity or recess of the sole plate above referred to. Heretofore, the method of manufacture has involved the following steps. Some of the refractory insulating cement moistened with water is first placed directly in the cavity or recess of the sole plate or casting, after which the heating element is positioned in proper place upon the cement. The heating element is then covered by placing more of the insulating material over it and the previously deposited material. Pressure is then applied to the insulating material to compact it in place. The material is then allowed to dry slowly to eliminate the moisture, and finally the unit is burned or fired to set the cement and remove smoke and fumes from the organic material usually present in it. In some instances, intermediate drying operations are employed, depending upon the consistency of the insulating material or mixture and the shop procedure of the manufacturer.

This prior process has certain serious objections, the chief of which are the multiplicity of steps or operations necessary and the extensive handling required. In an article such as an electric flat-iron, which is plated and buffed to a mirror finish, it is desirable to reduce to a minimum the handling of the plated sole plate in which the heating unit is to be imbedded. The imbedding material which is commonly employed is usually extremely abrasive, such material usually having a large percentage of fused aluminum oxide, granulated zirconium silicate, ground quartz or the like. If the material comes into contact with the plated sole plate, there is likely to be produced on the sole plate undesirable scratches which, even though slight, may permanently injure the

plate from the standpoint of appearance and later sale of the completed article. This is very apt to happen, and frequently does happen, in the use of the prior method or process above described.

The present invention has for its principal object, therefore, the provision of a novel process which eliminates the objections of the prior process and which produces a superior product.

A more specific object of the invention is to provide a process which involves a minimum number of steps and minimum handling of the plated sole plate of the article, and which substantially eliminates the possibility of injury to the plated surfaces of the iron.

The invention may be clearly understood from the following description with reference to the accompanying drawings, in which

Fig. 1 illustrates the heating element in its initial condition;

Fig. 2 is a perspective view of the preformed heating unit formed by the process;

Fig. 3 is a similar view of another preformed part;

Fig. 4 is a perspective view of the heating unit at a later stage in the process;

Fig. 5 is a perspective view of the sole plate of the flat-iron;

Fig. 6 is a perspective view of the cover plate sections;

Fig. 7 is a perspective view of the sole plate with the preformed unit applied thereto;

Fig. 8 illustrates the final step of the process; and

Fig. 9 is a cross-sectional view of the completed product.

In accordance with the preferred form of the process, the heating element is first formed as illustrated in Fig. 1, and the preformed heating unit shown in Fig. 2 is then formed by molding refractory insulating material around the heating element. This may be done by any of the methods well known in the ceramic molding art. Preferably, the flat-iron and the heating unit therefor is of the form disclosed and claimed in my copending application, Serial No. 716,874, filed March 22, 1934 and the sole plate of the iron is of the form illustrated in Fig. 5. For this reason, the preformed unit in its initial stage preferably takes the form of a stick or bar, as shown in Fig. 2, with spaced notches which may be readily formed during the preforming operation and the purpose of which will be explained presently. The heating element, whose terminals are shown at 2, is entirely surround-

ed by the insulating refractory material 3. The dimensions of this preformed unit conform with the dimensions of the cavity or recess of the sole plate so that it may fit easily therein.

5 In accordance with the invention, a refractory insulating material is used which will flow or extrude in the dry state under applied pressure. I find that the addition of talc to the usual mixture of clay and refractory grains assists this flow. The talc content may be as large as 100% of the weight of the grain used. However, a good mixture for practicing my invention consists of 50% fused alumina grain of about 150 size, 25% talc, and 25% refractory clay. These proportions constitute a little more than enough talc and clay to fill the interspaces between the grains, so that the grain and filler will extrude and flow under pressure. The proportions given are not the only proportions which may be used, and 20 may vary considerably, depending upon the electrical characteristics, temperature of operation of the unit, etc. As the size of the refractory grains also determines the mobility thereof, this is a factor to be considered. A suitable organic 25 binder such as is used in making foundry cores may be added to the mix in sufficient quantity to render the preform coherent, and to permit of rough handling.

Following the formation of the preformed unit 30 shown in Fig. 2, using a mobile mixture or material as above described, the unit is allowed to dry by letting it stand for a few days. The unit is then baked at a temperature of 500° to 600° F. to remove the organic material usually present 35 and to remove also the smoke and fumes caused thereby. The preformed unit is then ready to be placed in the channel or recess of the sole plate. In this state, the unit is sufficiently hard to permit of rough handling and to substantially 40 eliminate the presence of any loose abrasive particles, but it is brittle and capable of being crumpled or crushed by relatively high pressure.

Referring to Figs. 4 and 5, the preformed unit 45 is bent at the notches above mentioned and formed to the shape shown in Fig. 4 to adapt it for insertion in the channel or recess 4 of the sole plate 5, the brittle insulating material breaking at the points of bend. The sharp bending of the unit at the notches 4 and the consequent 50 breaking of the insulating material exposes the heating element at the corners 6, or at least renders the insulating material thin at those points, and the voids formed at these corners when the unit is placed in the channel 4 are filled by means 55 of the preformed triangular pellets or inserts 7, such as illustrated in Fig. 3. These small inserts may be formed of the same insulating material and in the same manner as the unit itself. The sole plate with the preformed heating unit 60 and inserts 7 applied thereto is shown in Fig. 7.

After the shaped preformed unit is placed in the recess or channel of the sole plate, the cover plate or cap illustrated in Fig. 6 is placed over the unit in the channel. The cover plate may 65 comprise two sections 8 as illustrated, shaped in conformity with the channel and formed of sheet metal. The edges of the cover plate sections are bent downwardly so as to engage the side walls of the channel when the sections are expanded 70 therein.

The sole plate with the assembled heating unit is then placed in a hydraulic press or like device, as illustrated in Fig. 8, and pressure is applied to the cover plate or cap sufficient to crush or 75 crumble the refractory material and consolidate

it in intimate contact with the walls of the channel or recess. This pressure may be in the neighborhood of 3 tons to the square inch of exposed cap surface. Very little, if any, displacement of the heating coil results, so that the necessary clearance between the channel wall and the coil is maintained. The sole plate structure is now completed and ready for application of the usual cover and handle, after which the flat-iron is completed and ready for use. It is unnecessary to fire or bake the heating unit after it has been pressed into the sole plate or casting.

The completed sole plate structure is illustrated in Fig. 9. The downwardly-turned edges of the cover plate or cap are expanded outward 15 against the side walls of the channel when the pressure is applied as above described, thus locking the cover plate in place. The cover plate or cap prevents the escape of any of the material of which the unit is formed around the edges of 20 the pressing punch or after the unit is in service. It also serves to carry the heat which arises from the heating coil back into the sole plate or casting, particularly by virtue of the contact of its edges or flanges with the side walls of the channel. As previously mentioned, this structure 25 forms the subject of a copending application.

It will be seen that this process reduces to a minimum the handling of the sole plate in the presence of the refractory material. The said 30 material is brought into association with the sole plate only when the solid preformed heating unit is placed in the channel and pressed to its final condition. At no time is there any loose moist cement or abrasive material in the vicinity of the 35 sole plate.

The process is simple and involves a minimum number of steps or operations and at the same time it results in an improved article. The finished product is compact and durable and fully 40 able to withstand severe usage throughout the life of the iron.

Although the process has been described herein in a specific embodiment and with particular reference to a flat-iron, it will be understood that 45 the invention is not thus limited but is capable of modification within the scope of the appended claims. The heating unit and the sole plate accommodating the same need not take the specific forms illustrated, the invention contemplates broadly the formation of the preformed unit and its later application to the sole plate. Moreover, the process may be modified as to its details.

I claim:

1. In the manufacture of electric appliances, such as flat-irons, the method which comprises initially preforming an electrical heating unit by molding about a current conductor a body of mobile refractory insulating material shaped to fit in a cavity or recess of the appliance thus forming a self-supporting unit comprising only the insulating material and the embedded conductor, placing the preformed unit in the said cavity or recess with said insulating material contacting the walls of said cavity, and subjecting the unit to pressure sufficient to crush and consolidate the unit in its cavity.

2. In the manufacture of electric appliances, such as flat-irons, the method which comprises 70 initially preforming an electrical heating unit by molding about a current conductor a body of mobile refractory insulating material shaped to fit in a cavity or recess of the appliance thus forming a self-supporting unit comprising only the 75

insulating material and the embedded conductor, placing the preformed unit in the said cavity or recess with said insulating material contacting the walls of said cavity, covering the unit with 5 a sheet metal cap to seal the said cavity or recess, and applying pressure to said cap sufficient to crush and consolidate the unit in the cavity and to lock the cap therein.

3. In the manufacture of electric appliances, 10 such as flat-irons, the method which comprises initially preforming an electrical heating unit by molding completely about a current conductor a body of mobile refractory insulating material shaped to fit in a cavity or recess of the 15 appliance thus forming a self-supporting unit comprising only the insulating material and the embedded conductor, placing the preformed unit in the said cavity or recess with said insulating material contacting the walls of said cavity, covering the unit with a sheet metal cap having 20 turned-down edges to seal the said cavity or recess, and applying pressure to said cap sufficient to crush and consolidate the unit in the cavity and to lock the cap therein.

25 4. In the manufacture of electric appliances, such as flat-irons, the method which comprises initially preforming an electrical heating unit by molding completely about a current conductor a body of mobile refractory insulating material 30 containing material shaped to fit in a cavity or recess of the appliance thus forming a self-supporting unit comprising only the insulating material and the embedded conductor, placing the preformed unit in the said cavity or recess with 35 said insulating material contacting the walls of said cavity, and subjecting the unit to pressure sufficient to crush and consolidate the unit in its cavity.

5. In the manufacture of electric appliances, 40 such as flat-irons, the method which comprises initially preforming an electrical heating unit by molding completely about a current conductor a body of mobile refractory insulating material shaped to fit in a cavity or recess of the appliance 45 thus forming a self-supporting unit comprising only the insulating material and the embedded conductor, said material containing an extrudable filler capable of flowing under pressure when dry, placing the preformed unit in the said cavity or 50 recess with said insulating material contacting the walls of said cavity, and subjecting the unit to pressure sufficient to crush and consolidate the unit in its cavity.

6. In the manufacture of electric appliances, 55 such as flat-irons, the method which comprises initially preformed an electrical heating unit by molding completely about a current conductor a body of mobile refractory insulating material shaped to fit in a cavity or recess of the appliance 60 thus forming a self-supporting unit comprising

only the insulating material and the embedded conductor, drying the preformed unit, placing the preformed unit in the said cavity or recess with said insulating material contacting the walls of said cavity, and subjecting the unit to pressure 5 sufficient to crush and consolidate the unit in its cavity.

7. In the manufacture of electric appliances, such as flat-irons, the method which comprises initially preforming an electrical heating unit 10 by molding completely about a current conductor a body of mobile refractory insulating material shaped to fit in a cavity or recess of the appliance thus forming a self-supporting unit comprising only the insulating material and the embedded 15 conductor, baking the preformed unit, placing the preformed unit in the said cavity or recess with said insulating material contacting the walls of said cavity, and subjecting the unit to pressure 20 sufficient to crush and consolidate the unit in its cavity.

8. In the manufacture of electric appliances, such as flat-irons, the method which comprises initially preforming an electrical heating unit 25 by molding completely about a current conductor a body of mobile refractory insulating material shaped to fit in a cavity or recess of the appliance thus forming a self-supporting unit comprising only the insulating material and the embedded 30 conductor, drying the preformed unit, baking the unit, placing the preformed unit in the said cavity or recess with said insulating material contacting the walls of said cavity, and subjecting the unit to pressure sufficient to crush and 35 consolidate the unit in its cavity.

9. In the manufacture of electric appliances, such as flat-irons, the method which comprises performing a stick-like electrical unit by molding about a current conductor a body of mobile refractory insulating material dimensioned to fit 40 in a cavity or recess of the appliance and provided with spaced notches, bending said unit at the said notches to shape it in conformity with said cavity or recess, placing the shaped unit in the said cavity or recess together with inserts 45 at the bent notched portions of the unit, and subjecting the unit to pressure sufficient to crush and consolidate the unit in its cavity.

10. In the manufacture of electric appliances, such as flat-irons, the method which comprises 50 performing a stick-like electrical unit by molding about a current conductor a body of mobile refractory insulating material dimensioned to fit in a cavity or recess of the appliance, bending said unit to shape it in conformity with said cavity or recess, placing the shaped unit in the said cavity or recess, and subjecting the unit to pressure sufficient to crush and consolidate the unit in its cavity.

JOSEPH W. MYERS. 60
